VALVE BAG

Alfred Du Bois, Paris, France

Application March 12, 1936, Serial No. 68,399
In France October 11, 1935

5 Claims. (Cl. 229—62.5)

My invention relates to valve bags, more particularly to flat bottom bags, and its main object is to adapt this kind of bag for filling by means of a spout to be inserted obliquely downwards into the bag which is maintained in substantially vertical position.

In the known bags, the use of an oblique spout is only possible when using a spout of cross section much smaller than valve section, which considerably diminishes bag filling speed. However the use of an oblique spout is necessary in the case of filling a bag simply by gravity.

My invention consists in part of an outer valve lip, composed of a member applied on the bottom and sufficiently flexible and elastic as to allow of its being forced back by action of an oblique filling spout and to return to its closing position after removing the spout.

One may utilize, for example, to this end a member of crepe paper fabric, flexible matter such as rubber, etc.

It has been already proposed to constitute, in a manner similar to the aforesaid, the inner valve lip, but it was thus endeavoured to ensure a better closing of the valve, while the aforesaid problem is quite different and nowise solved by this former particular means.

It is also a common practice in the aforesaid bags to constitute the outer bag lip, at least partially, by a member applied on the bottom and generally comprising a piece of pasteboard or strong paper, but that piece possesses a certain stiffness of its own and it is further so secured on the bottom as to act as if it were a rigidly integral part of the bottom so that it is unable to play independently of the bottom.

Other objects of the present invention will appear from the following description of an embodiment of my invention.

In the drawing:

Fig. 1 is a perspective view with pieces partly broken away, of the end of a flat bottom valve bag improved according to my invention;

Fig. 2 is a perspective view of the outwardly viewed end of the same bag;

Fig. 3 is also a perspective view of said bag, but shows the opposite end to that comprising the valve;

Fig. 4 is a cross section along the valve axis with filling spout in position, and

Fig. 5 is a horizontal view of the filling spout alone.

In the embodiment shown, the bag bottom is formed in the usual manner by the four over-

lapping panels 1, 2, 3, 4 among which panels 1, 2, 3 are secured together by clips 5, while panel 4 remains free and forms the inner valve lip. This panel 4 applies inwardly on a part of panels 2 and 3, which partly form the outer valve lip. The overlapping part of the inner and outer valve lips thus constituted being too short to ensure an adequate closing, there is applied beneath panels 2, 3 and secured to said panels by clips 6 a subsidiary panel. But, whilst this panel is usually formed by pasteboard and also secured to panels 2, 3 along edges AB and AC, it is constituted herein, according to my invention by crepe paper and secured to panels 2, 3 by the single cross row of clips 6, the edges AB and AC remaining free.

In this way, the subsidiary panel 7 may be folded up, without injury, as shown by Fig. 4, so as to give free passage to oblique filling spout 8. After removing the spout, panel 7 returns automatically by its own elasticity to its original closing position, as shown by Fig. 2 and thus forms a part of outer valve lip.

In order to facilitate the forcing back of panel 7, the filling spout 8 may be advantageously provided with a projecting member 9 shaped substantially as a stem.

It is to be understood that instead of crepe paper, many other materials might be used, even a relatively stiff material which would be so incised on the extension of line AA' as to open towards the right and the left like flaps on thrust of spout 8 and particularly of stem 9, and so flexible as to fall back of itself after removing spout 8.

Panel 7 might extend no farther than clips 6. In the present example however its presence has served to constitute by its inward extension 7' the closing valve flap referred to in the patent application of the same inventor filed on November 27, 1935, under Serial No. 51,731.

Fig. 3 shows an improved disposition of the bottom clips in order to facilitate construction of bag and this improvement forms another object of my invention.

According to this improvement clips 5 are first placed in corners E and F at a certain distance from point A. It is easy to do so by passing the arm of the clip-fastener through A' and the space above panel 10 and beneath panels 11 and 12. Then clips 5 are placed along sides A'G and A'H as well as between A and A', the clip-fastener arm then passing through A and the space left free beneath panels 11 and 12 and

above panel 13, since the clips at corners E and F do not extend to point A. The aperture left in A for passing the clip-fastener arm is narrow and does not at all impair the proper closing of bag. This disposition of clips relates of course only to bag bottom which comprises no valve.

Fig. 4 shows a further improvement also forming another object of my invention. The oblique filling spout 8 comprises at its lower part a projection 15 of substantially elliptical cross section. This projection 15 engages in the inner part of the valve, as shown in Fig. 4 and prevents bag inflation on filling from producing deformations of the valve and particularly any swelling of bottom KL which otherwise would come behind spout 8 and hinder its removal. Furthermore by preventing these deformations of the valve it ensures a regular play of the member 7 whose operation might be impaired by these deformations.

My invention is not intended of course to be limited by the detailed construction shown and described but only by the appended claims.

What I claim is:

1. A flat bottom valve bag having a four-angled bottom made up of four overlapping panel-like folded end portions of the bag walls three of which are secured together and one situated beneath the other remains free and forms the inner valve lip, the transverse edges of the side panels over said inner valve lip being obliquely directed with respect to the bag walls and thereby leaving uncovered a substantially triangular portion of that lip, a sheet-like member of flexible and somewhat resilient material provided under said side panels and over said inner lip to cover at least partially the said triangular portion, said member being secured partially only to said side panels and not to the inner valve lip to thereby have its outer end part forming over its whole width a free flap covering at least partly the said triangular portion.

2. A flat bottom valve bag having a four-angled bottom made up of four overlapping panel-like folded end portions of the bag walls three of which are secured together and the fourth partly overlapped by the two adjacent ones or

side panels remains free from them, a sheet-like free flap made of flexible and somewhat resilient material and having a width substantially equal to that of the bottom, located beneath said side panels and over said fourth panel to lie at least a portion of said side panels and to cover at least a portion of that part of the fourth panel which is not overlapped by the side panels, said free flap having within the valve an extension towards the interior of the bag and by means of which it is secured to the bottom so as to leave between said flap and said fourth panel a passageway through which a filling tube can be slid into the bag, that part of the free flap which covers the portion of the fourth panel not overlapped by the side panels being thus adapted to be resiliently crimped back by a filling tube inserted obliquely through the valve opening.

3. A flat bottom valve bag as in claim 2, wherein said free flap is made of supple paper.

4. A flat bottom valve bag as in claim 2, wherein said free flap is made of crepe paper.

5. A flat bottom valve bag having a four-angled bottom made up of four overlapping panel-like folded end portions of the bag walls three of which are secured together and the fourth situated beneath the two adjacent ones or side panels remains free from the bottom and forms the inner valve lip, the transverse edges of the side panels defining with said lip the valve opening and being obliquely directed with respect to the bag walls, thereby leaving uncovered between them a substantially triangular portion of that lip, a sheet-like member of flexible and somewhat resilient material and having a width substantially equal to that of the valve provided under said side panels and over said inner lip to cover at least partially the said triangular portion, said member being secured to the bottom in the rear only of a line perpendicular to the valve axis and passing through the meeting point of said transverse edges of the side panels and neither to that part of the side panels on each side of said triangular part nor to the inner valve lip, thereby forming a free flap.

ALFRED DU BOIS.
